(57) CLAIM

The ornamental design for a camping chair, as shown and described.

DESCRIPTION

FIG. 1 is a front perspective view of a camping chair according to my new design;
 FIG. 2 is a front view thereof;
 FIG. 3 is a rear view thereof;
 FIG. 4 is a right-side view thereof;
 FIG. 5 is a left-side view thereof;
 FIG. 6 is a top view thereof; and,
 FIG. 7 is a bottom view thereof.

The broken lines in the drawings depict portions of the camping chair that forms no part of the claimed design.
